UNITED STATES PATENT OFFICE.

MICHAEL J. WARD, OF YOUNGSTOWN, OHIO.

SHEET-FEEDING APPARATUS.

1,031,600.

Specification of Letters Patent. Patented July 2, 1912.

Application filed February 21, 1912. Serial No. 679,096.

To all whom it may concern:

Be it known that I, MICHAEL J. WARD, a citizen of the United States, residing at Youngstown, in the county of Mahoning and State of Ohio, have invented new and useful Improvements in Sheet-Feeding Apparatus, of which the following is a specification.

My invention relates to feeding mechanisms for sheet metal and its object is to combine a rotary cooling rack with a feed table for presenting the sheets to the rack by moving them substantially parallel to the axis of the rotary rack and directly into converging pockets or spaces between parallel lines of arms or spokes on the rack, so that the sheets may enter the said pockets or spaces without the necessity of changing their direction after leaving the rolls, or other sheet-treating apparatus. By my improvement additional mechanism or extra help commonly used to feed the sheets laterally to the cooling rack is dispensed with and considerable space saved.

Referring to the accompanying sheets of drawings, Figure 1 is a plan of my invention with a portion at the right broken away. Fig. 2 is a side elevation of the same. Fig. 3 is a section on the line III—III, of Fig. 1.

On the drawings, 1 is a horizontal rotary shaft of the cooling rack, and 2, 2 are the pillow-blocks in which the ends of the shaft are supported. The shaft has connected thereto the worm-wheel 3, driven by the worm 4 on the driving-shaft 5.

6 is the driving pulley connected to the shaft 5 and disconnected therefrom by the clutch 7 shown conventionally. The clutch is represented as operated by the foot-lever 8 and the clutch-levers 9 connected thereto. I have not attempted to show any particular form of clutch since the kind of clutch or even its presence forms no essential part of the present invention. The shaft may be given intermittent motion by various well-known means.

At selected places along the shaft 1 I secure the circular wheel-like supports 10 for the edges of the sheets 11 and the attachment of the spokes or arms 12. These spokes have their inner ends secured in the periphery or rim of the supports 10 and extend out therefrom preferably so as to form acute angles with the said rim at the forward side of the arms, that is, the side thereof facing the direction of their move-

ment. The arms 12 are arranged in longitudinal rows so that each two consecutive rows constitute a pocket or space for a metal sheet 11.

At one side of the rack I arrange the feed-table 13 divided into sections between the rear portions of which the arms 12 move upwardly as the rack rotates. Each section preferably has a pair of horizontal shafts 14 at right angles to the line of feed of the sheets to the table and at right angles to a vertical plane which includes the shaft 1. Feed rollers 15 are secured to these shafts. Horizontal sheet-guiding metal strips 16, 70 arranged lengthwise of the table, have their ends secured to their respective sections, the tops of the guides being slightly below the tops of the rollers and the front ends of the guides being inclined downwardly and toward the feeding-in end of the table, so that the sheets may be fed from section to section without their engagement with the ends of the guide strips. Each section of the table 13 has the vertical guide 17 along the 80 side nearest the shaft 1 to prevent the sheets from engaging the arm-supports 10, the forward ends of these guides being inclined toward the supports 10 to prevent the corners of the sheets from engaging the ends 85 of the guides.

18 represents a table from which the sheets are fed to the roller feed-table 13. I have not shown any means for positively feeding the sheets to the feed table 13, but suitable 90 means will suggest themselves to those acquainted with the art to which this invention belongs.

The shafts 14 are provided with the pulleys 19, there being between the pulleys in each section of the table 13 an idler 20 having its lower side below the tops of the adjacent pulleys. The metal belt, chain, or cable 21 runs over the pulleys 19 and under the idlers 20, around the sprocket 22 secured 100 beneath the top of the table 13, and around the driving pulley 23 on the shaft 24. The shaft 24 is driven from the shaft 25 by the belt, chain, or cable 26, and the shaft 25 is driven through suitable gearing from the shaft 27 to which the drive pulley 28 is connected.

29 is a gage or stop arranged at the rear end of the table 13 so as to stop the feed of the sheets at a predetermined place.

I place the table or truck 30 or equivalent device at the opposite side of the cooling

rack from the table 13 to receive the sheets as they are discharged from the rack. The height of the table 13 and the inclination of the arms 12 are such that, at each step by step movement of the rack, a row of arms 12 may be brought into horizontal position just beneath the level of the guide-strips 16, as shown on Figs. 2 and 3. The parts being as shown on the drawings, a hot sheet 10 is fed to the table 13 from any selected sheet-feeding or sheet-treating device, the feed rollers being rotated by power applied to the pulley 28 so as to carry the sheet, which rides on the feed rollers, into a pocket 15 or feed space between the horizontal row of arms 12 beneath the sheet and a row of arms a short distance above the sheet. The sheet is stopped by engagement with the gage 29 or by any other suitable means. The operator then steps on the foot-lever 8 which through the levers 9 operates the selected form of clutch 7 so as to connect the constantly running pulley 6 to the worm-shaft 5. The cooling rack rotates so as to cause 25 the horizontal row of arms 12 to lift the said sheet above the feed table 13 and to bring the next succeeding row of arms into horizontal position just below the top of the table 13. Another hot sheet is fed to the 30 table 13 as just described in connection with the first sheet, and the cooling rack is then rotated another step and the next row of arms 12 is brought into the said horizontal position. Other sheets are successively fed to the table 13 and carried away by the cooling rack. When the sheets are transferred to the opposite side of the rack and arrive at their angle of start, they slide down the arms 12 onto the receiving truck or table 30.

40 I claim—

1. The combination with a rotary cooling-rack having its axis of rotation horizontal and its periphery provided with longitudinal rows of arms forming spaces between consecutive rows of arms, of a feed-table for

sheets arranged parallel with the said axis, means for feeding sheets on the table lengthwise into the said spaces, and means for rotating the cooling rack so as to cause a row of arms beneath a sheet to lift the sheet 50 from the table and bring the next succeeding row of arms into position to form with the preceding row of arms a space for another sheet fed thereto on the said table.

2. The combination with a rotary cooling-rack having its axis of rotation horizontal and having its periphery provided with vertical circles of outwardly extending arms arranged in longitudinal rows so as to form spaces between consecutive rows, of a horizontal feed-table at one side of the said rack, the feed-table having therein transverse spaces each arranged to receive one of the said circle of arms, and means for rotating the cooling rack so as to cause a row of arms 65 beneath a sheet to lift the sheet from the table and bring the next succeeding row of arms into position to form with the preceding row of arms a space for another sheet fed thereto on the said table. 70

3. The combination with a horizontal table having transverse spaces at one edge, and means for feeding sheets thereon transversely across the said spaces, of a rotary shaft parallel with the table and having outwardly-projecting circles of arms extending into the said spaces, and arranged in longitudinal rows, and means for rotating the shaft so as to cause a row of arms beneath a sheet to lift the sheet from the table and 80 bring the next succeeding row of arms into position to form with the preceding row of arms a space for another sheet fed thereto on the said table. 75

Signed at Youngstown, Ohio, this 16th 85 day of February, 1912.

MICHAEL J. WARD.
